HYDROPNEUMATIC RECUPERATOR WITH
ADJUSTABLE POWER

Jacques Emilien Prache, Fontenay-sous-Bois,
France, assignor to Societe des Forges et Ateliers du Creusot, Paris, France, a joint-stock company

Application April 17, 1950, Serial No. 156,248
In France April 20, 1949

4 Claims. (Cl. 89—43)

1

This invention relates to hydro-pneumatic recuperators especially adapted for use with artillery intended to fire at relatively large angles of elevation, and is particularly directed to improvements in the recuperators disclosed in Figs. 1 and 2 of copending application Serial No. 743,998, filed April 25, 1947.

The principal object of the present invention is the same as that of the above mentioned copending application, namely, to provide novel means for automatically regulating, as a function of the angle of elevation of the gun, the power possessed by the recuperators of braking and of returning into battery position without modifying their initial latent energy. This result is obtained by varying the initial volume of the air subjected to compression during recoil (which may be designated as the "useful air") in accordance with changes in the laying angle, but without changing its pressure.

As the result of a thorough study of recuperators of the character illustrated in Figs. 1 and 2 of application Serial No. 743,998, wherein a liquid medium is displaced during recoil of the gun and serves to compress the useful air in a compartment of variable volume constituting the forward end of the air reservoir, it has been found that, as the angle of fire approaches the vertical, there is an increasing tendency for the liquid of the recuperator to leak into the rear compartment of the air reservoir wherein is confined the mass of air which is protected from the effect of the recoil.

It is therefore a particular object of the present invention to overcome this disadvantage of the prior structures either by interposing a floating piston between the separating piston which divides the air reservoir into the two compartments and the orifice through which the liquid flows into said reservoir to compress the air, thereby ensuring separation of the two fluids, or by so changing the positions of the elements that the compartment containing the air which is to be protected from the effect of the recoil is located in front of, rather than to the rear of, the separating piston, and that the orifice between the recuperator cylinder containing the liquid and the compartment containing the mass of air which is to be compressed is located at the rear end of said compartment. In the latter embodiment, the separating piston will, of course, be controlled in such a manner that its displacements are opposite to those received by the pistons in the corresponding embodiments of application Serial No. 743,998.

2

Referring now to the drawings, wherein like reference characters indicate like parts throughout the several views;

Fig. 1 is a diagrammatic sectional elevation 5 of a hydro-pneumatic recuperator constituting one embodiment of the invention;

Fig. 2 is a similar view of a modification of the arrangement shown in Fig. 1; and

Fig. 3 is a similar view of another form of recuperator wherein the improvement of the present invention is applied similarly to Fig. 2.

The devices shown in Figs. 1 and 2 are of basically the same construction as that of Fig. 15 of application Serial No. 743,998, while Fig. 3 herein is comparable to Fig. 2 of the earlier case.

In the embodiment of the invention illustrated in Fig. 1, the recuperator comprises a cylinder 1 connected to and movable with the cradle 2 which oscillates about horizontal trunnions 3 on the gun carriage 4 during laying of the gun in elevation. Movable in the cylinder 1 is a piston 5 which is connected to a member 6 forming part of the recoiling mass of the gun, and which, when the recoil takes place, forces liquid from the cylinder 1 into an air reservoir 7 formed integrally with said cylinder and with which the latter communicates freely through a channel 8 and an orifice 8a. In the structure shown, the orifice 8a leads into the front portion of the reservoir 7, i. e. the end thereof closest to the muzzle of the gun. The interior of the reservoir 7 is divided into two compartments *a* and *b* by a separating piston 9 having a rod 9a which extends in an airtight manner through the rear end of the reservoir and carries at its outer end a roller 10 which, when the gun is elevated, is constrained to follow an arcuate path defined by a guide or directing groove 11 integral with or fixed to the gun carriage 4 and having a suitable profile for the purpose hereinafter described.

The separating piston 9 is provided with a passageway or conduit 9b extending therethrough in a direction parallel to the piston rod 9a and wherein is mounted a valve 13 which is maintained in open or unseated position when the gun is at rest by a relatively weak spring 14, thus permitting air to pass between the two compartments *a* and *b*. As soon as recoil begins, the valve 13 closes and interrupts communication between the two compartments throughout the recoil movement and until the end of the return movement to battery position. The piston 55 9 may, if desired, be provided with a compensat-

ing piston rod 15 of the same diameter as rod 9a and extending in the opposite direction to the latter so as to equalize the areas of the opposite faces of the piston 9 which are subjected to the pressure of the air in the compartments *a* and *b*.

According to the present invention, the reservoir 7 also houses a movable fluid-tight partition or floating piston 7a interposed between the orifice 8a and the separating piston 9 and normally abutting, when the gun is at rest, against stops 7b located in a transverse plane immediately to the rear of the orifice 8a. When the compensating piston rod 15 is employed, it passes through the floating piston 7a in such a manner that there may be relative axial movement between the two elements, suitable packing being provided for forming a fluid-tight seal therebetween. The piston 7a also carries similar packing for sealing its outer periphery against the surrounding wall of the reservoir 7.

When, under the action of the gun elevating mechanism, the cradle 2 is subjected to a positive angular displacement about the trunnions 3, the roller 10, moving in the groove 11, causes the piston 9 to slide toward the front of the reservoir 7. During this displacement of the piston, the chambers *a* and *b* remain in communication with one another, the spring 14 being so calibrated as to maintain the valve 13 in open position even when the angular velocity of the gun laying movement is at a maximum. There is then an exchange of air between chambers *a* and *b* without any variation in pressure, the total volume remaining constant. The chamber *a*, which is intended to confine the volume of useful air which is subject to compression during recoil, thus changes in volume as a function of the angle of elevation of the gun, according to the law imposed by the profile of the groove 11.

When the gun is fired, after having been laid at any desired angle of elevation, the recoiling member 6 draws the recuperator piston 5 rearwardly in the cylinder 1 and thereby forces liquid from said cylinder through the channel 8 and orifice 8a into that portion of the reservoir 7 which lies in front of the floating piston 7a, forming the chamber 7c. It will be understood that the chamber 7c, the channel 8 and the portion of cylinder 1 lying to the rear of piston 5 are always completely filled with liquid, and that the portion of cylinder 1 in front of the piston 5 may be vented to the atmosphere through an orifice 1a. As the recoil continues, the additional liquid which is forced into the chamber 7c pushes the floating piston 7a rearwardly so as to compress the air confined between it and the piston 9, the valve 13 closing as soon as the floating piston 7a starts its rearward movement. Compression of the air in the compartment *a* during recoil thus stores up energy which is effective during counter-recoil to return the gun to battery, the amount of power stored depending solely upon the volume of the chamber *a* at the angle of elevation of the gun at the time of firing.

During the return to battery, the floating piston 7a is moved forwardly and returned to its initial position abutting the stops 7b by expansion of the air in compartment *a*, and the excess liquid in chamber 7c is forced back through the orifice 8a and channel 8 into cylinder 1 as the piston 5 also moves forwardly to its original position. Since the air pressure in compartment *a* remains greater than that existing in compartment *b* until the return to battery position is completed, the valve 13 remains closed through-

out recoil and counter-recoil and reopens only when the gun has come to rest, at which time the pressures in compartments *a* and *b* are equal and the spring 14 is effective to open the valve and reestablish communication between the two compartments.

It will be apparent from the foregoing description that the floating piston 7a constitutes a barrier against leakage of liquid from the chamber 7c into the air compartments *a* and *b* which is effective at all times regardless of the angle of elevation of the gun.

In the structure shown in Fig. 2, the floating piston 7a and channel 8 of Fig. 1 are omitted; the piston rod 9, and compensating piston rod 15 are lengthened and shortened, respectively, so that the piston 9 is adjacent the front, rather than the rear, end of reservoir 7 when the gun is horizontal; the relative disposition of the compartments *a* and *b* of the reservoir is reversed in comparison with the embodiment of Fig. 1; and the orifice 8a through which the liquid flows from the cylinder 1 into the reservoir 7 is located at the rear end of the compartment *a* and provides direct communication between said compartment and said cylinder. The valve 13 in Fig. 2 is also inverted relatively to the position shown in Fig. 1. Since the separating piston 9 in the embodiment of Fig. 2 must be displaced rearwardly as the elevation angle of the gun increases, the guide or directing groove 11 in which the roller 10 operates is also differently shaped and positioned relatively to the trunnions 3 than in the embodiment of Fig. 1.

It will be readily apparent that, with the arrangement shown in Fig. 2, leakage of liquid into compartment *b* is effectively prevented because, at all angles of elevation of the gun above the horizontal, gravity itself opposes any tendency of the liquid to flow forwardly between the piston 9 and the surrounding wall of the reservoir 7. It will be understood, of course, that the fit of the piston 9 in the reservoir 7 is sufficiently tight to prevent such leakage when the gun is horizontal.

The embodiment of the invention illustrated in Fig. 3 is basically the same as that of Fig. 2 except that communication between the compartments *a* and *b* is effected through a by-pass conduit 17 in the wall of the reservoir 7, instead of through a valve-controlled passageway in the piston 9, the latter being solid in the device of Fig. 3. The flow of air between compartments *a* and *b* through the conduit 17 is controlled by a cock 16 which is positively actuated in any suitable manner, as by a dog 18 having arms of unequal lengths, said dog being fixed to and carried by the member 6 of the recoiling mass and acting on a crank arm 19 connected to the cock. When the gun is in battery, the cock 16 is in the open position illustrated in Fig. 3; but as soon as the recoil begins, it is closed by the forward or shorter leg of the dog 18 which, after the closing, releases the crank 19 and leaves it in a position such that, upon counter-recoil and return of the gun to battery, the rear or longer leg of the dog 18 engages the crank and reopens the cock. The by-pass conduit 17 is of such length as to open into the compartments *a* and *b* at suitable points on either side of the extreme positions of the piston 9.

The arrangement of Fig. 3 is similar to, and functions in substantially the same manner as, the device of Fig. 2 of application Serial No. 743,998, but differs therefrom in that the relative positions of the compartments *a* and *b* are

reversed, and the orifice 8_a through which the cylinder 1 and air reservoir 7 communicate is located to the rear, instead of in front, of the piston 9 . Leakage of liquid from compartment a into compartment b is prevented in the same manner as that previously described in connection with the embodiment of Fig. 2 herein.

The devices of the present invention have the same basic advantages and utility as those of application Serial No. 743,998, but are additionally beneficial in that they embody means for effectively preventing the liquid of the recuperator cylinder from gaining access to that compartment of the air reservoir wherein is contained the mass of air which is protected from the effect of the recoil.

What is claimed is:

1. In a hydro-pneumatic recuperator for a gun of the variable power type wherein the accumulation of recuperating energy results from movement of the recoiling mass of the gun and the amount of energy accumulated varies with the angle of elevation of the gun prior to recoil, a cylinder movable to various angular positions relative to the horizontal in accordance with the angle of elevation of the gun, a piston in said cylinder located adjacent the forward end thereof when the gun is at rest, the portion of said cylinder to the rear of said piston being filled with a liquid, a piston rod connecting said piston to the recoiling mass of the gun, an air reservoir fixed to and movable with said cylinder to various angular positions relative to the horizontal, a piston in said air reservoir separating the latter into two compartments, one of said compartments containing air adapted to be compressed during recoil of the gun and the other compartment containing air which is protected from the recoil effect, means for varying the position of said separating piston in said reservoir according to the angle of elevation of the gun prior to recoil, means providing free communication for the flow of liquid from said cylinder into said first named compartment of said reservoir, and means independent of said separating piston effective at all angles of elevation of the gun for preventing the leakage of liquid into said second named compartment.

2. In a hydro-pneumatic recuperator for a gun of the variable power type wherein the accumulation of recuperating energy results from movement of the recoiling mass of the gun and the amount of energy accumulated varies with the angle of elevation of the gun prior to recoil, a cylinder movable to various angular positions relative to the horizontal in accordance with the angle of elevation of the gun, a piston in said cylinder located adjacent the forward end thereof when the gun is at rest, the portion of said cylinder to the rear of said piston being filled with a liquid, a piston rod connecting said piston to the recoiling mass of the gun, an air reservoir fixed to and movable with said cylinder to various angular positions relative to the horizontal, a piston in said air reservoir separating the latter into two compartments, the compartment forward of said piston containing air adapted to be compressed during recoil of the

gun and the compartment to the rear of said piston containing air which is protected from the recoil effect, means for varying the position of said separating piston in said reservoir according to the angle of elevation of the gun prior to recoil, said separating piston being located adjacent the rear end of said reservoir when the gun is horizontal and being movable forwardly as the angle of elevation increases, means including an orifice in the wall of said reservoir adjacent the forward end thereof providing free communication for the flow of liquid from said cylinder into said reservoir, and means effective at all angles of elevation of the gun for preventing the leakage of liquid into the air compartment to the rear of said separating piston including a floating piston in said reservoir interposed between said orifice and said separating piston.

3. A recuperator as claimed in claim 2 including a conduit filled with liquid connecting the rear end of said cylinder with said orifice, the portion of said reservoir in front of said floating piston also being filled with said liquid, and means for limiting the forward movement of said floating piston to a position immediately to the rear of said orifice.

4. In a hydro-pneumatic recuperator for a gun of the variable power type wherein the accumulation of recuperating energy results from movement of the recoiling mass of the gun and the amount of energy accumulated varies with the angle of elevation of the gun prior to recoil, a cylinder movable to various angular positions relative to the horizontal in accordance with the angle of elevation of the gun, a piston in said cylinder located adjacent the forward end thereof when the gun is at rest, the portion of said cylinder to the rear of said piston being filled with a liquid, a piston rod connecting said piston to the recoiling mass of the gun, an air reservoir fixed to and movable with said cylinder to various angular positions relative to the horizontal, a piston in said air reservoir separating the latter into two compartments, the compartment to the rear of said separating piston communicating with the liquid filled portion of said cylinder and containing air adapted to be compressed by said liquid during recoil of the gun and the compartment forward of said piston containing air which is protected from the recoil effect, means for varying the position of said separating piston in said reservoir according to the angle of elevation of the gun prior to recoil, said separating piston being located adjacent the forward end of said reservoir when the gun is horizontal and being movable rearwardly as the angle of elevation increases, and an orifice in the wall of said reservoir adjacent the rear end thereof providing free communication for the flow of liquid from said cylinder into the compartment of said reservoir to the rear of said separating piston, the location of said orifice assisting in preventing the leakage of liquid into the air compartment forward of said separating piston at all angles of elevation of the gun.
